UNITED STATES PATENT OFFICE.

CHARLES H. BARROWS, OF WILLIMANTIC, CONNECTICUT.

SYSTEM OF ELEVATED AND SURFACE RAILWAYS.

SPECIFICATION forming part of Letters Patent No. 517,535, dated April 3, 1894.

Application filed May 17, 1893. Serial No. 474,543. (No model.)

To all whom it may concern:

Be it known that I, CHARLES H. BARROWS, a citizen of the United States, residing at Willimantic, in the county of Windham and State 5 of Connecticut, have invented certain new and useful Improvements in Systems of Elevated and Surface Railways; and I do hereby declare the following to be a full, clear, and exact description of the invention, such as 10 will enable others skilled in the art to which it appertains to make and use the same.

My present invention relates to a system of elevated and surface railways in which I provide an elevated structure to accommodate 15 trains adapted to travel at high speed between main stations of a railway without danger of obstructions common to surface railways, while on the surface of the ground I employ a single rail track and cars adapted 20 to travel at a comparatively slow speed, to stop at frequent intervals for the accommodation of the traveling public, and which can be run to any desired points or places to convey the passengers to the main station, so 25 that the passengers can transfer from the slow moving surface cars to the rapid elevated cars and be quickly conveyed by the latter from one main station to another.

In my new system of railways I employ cars 30 of light construction to be propelled by electric power and run at frequent intervals as distinguished from long heavily loaded trains running at long intervals of time; and by this system I utilize the surface lines as feeders 35 to the elevated rapid cars which are designed principally as a means for quickly transporting suburban residents to the principal station or stations in a large city.

In addition to the foregoing objects I aim 40 to reduce the cost of track construction and maintenance in elevated and surface railways, to avoid derailment, and to simplify the construction of both the track and cars, thereby effecting economy in the primary construction and maintenance of the railway.

The first part of my invention resides in the elevated structure in which I employ two longitudinal girders, and a central guide rail between the girders, which parts constitute 45 the track on which are run the elevated cars. Each girder may be constructed of wood planks, or of metal, or of wood and metal to-

gether; and the several pieces are arranged to break joints and are held by transverse fastenings that unite the several parts securely together. The side girders and central guide rail are laid so that their upper surfaces are in about the same level, and on these side girders travel broad flangeless bearing-wheels of the front and rear trucks of the 55 locomotive or car, and on the guide rail between the girders ride the flanged guide wheels carried by the forward and rear axles of the car or locomotive. The body of the locomotive is so arranged or hung that the 60 greater part of the weight thereof is thrown on the larger flangeless driving wheels at the rear of the locomotive to secure the necessary traction between said flangeless drive wheel and the girders on which they ride or bear; 65 while the central flanged wheels of the forward and rear trucks serve as the means for guiding the locomotive or car to cause it to keep to the track and reduce the liability of derailment to a minimum. 70

In elevated structures, a train of cars is employed consisting of a locomotive carrying the electric motor for driving the rear axle, and one, two or more passenger coaches, each coach provided with front and rear trucks, 75 the axles of which are provided with the broad tread flangeless wheels and with centrally aligned flanged wheels that ride on the central guide rail of the track.

In the surface lines of railways that serve 80 as feeders to the elevated main lines, I provide a single bearing rail which may be laid on a suitable road bed, and employ an electrically propelled car which has its front truck furnished with aligned flanged wheels 85 that ride on the rail and the rear truck has its axle provided with a large flanged wheel and with broad tread flangeless wheels that are adapted to travel on the ground, or on planks or other supports laid on the ground, 90 the car body being so hung or arranged that the single rail will bear its proportion of the weight of said car body while the broad flangeless wheels on the rear axle cause the car to maintain its upright proper position. 95 And the invention further consists in the combination of devices and peculiar construction and arrangement of parts as will be hereinafter fully described and claimed. 100

In the accompanying drawings, forming a part of this specification, I have illustrated the preferred embodiment of my invention, in which—

- 5 Figure 1 is a side elevation of my elevated and surface railway, and Fig. 2 is an end view showing cars on the elevated and surface railways. Fig. 3 is an enlarged plan view of a portion of the girders and guide rail forming 10 the track of the elevated railway. Fig. 4 is a plan view of the running gear for an electrically propelled car on the elevated railway. Fig. 5 is a plan view of the running gear for a "trailing" coach to be coupled to the electrically propelled car on the elevated or surface railway. Fig. 6 is a plan view of the trucks or running gear for an electrically-propelled car specially designed for a surface railway.

20 Like letters of reference denote corresponding parts in all the figures of the drawings.

A designates the track for the elevated structure to sustain the elevated rapid train of cars traveling between main stations on 25 the line of the railway. This elevated track is supported at a suitable height by vertical columns and trestle work constructed in any approved manner to afford the necessary stability and security for the elevated train of 30 cars, and said track consists of the girders B, B, and the guide rail C, the latter situated between and equi-distant from the girders B, B, and the whole being united or tied together by any approved appliances to insure 35 the girders and rail remaining in their proper relative positions. Each girder is constructed to provide a broad bearing surface for the broad flangeless wheels of the cars to ride upon so as to maintain the cars in their up- 40 right positions; and each girder is constructed of a series of sections a, b, c, arranged so that the ends break joints with each other, and they are united together by transverse fastenings so as to present a solid substantial 45 structure with a practically level upper surface. The girder may be constructed of wooden planks arranged laterally in contact with each other to present their edges to the faces or treads of the broad flangeless car- 50 wheels, and united together by through bolts; D which pass transversely through the planks; or the girder may be built up of metallic plates or bars, or it may consist of wood and metal parts united together, the object being 55 to provide a cheap, strong and durable girder or sleeper devoid of the usual rail and having a broad bearing surface for the flangeless car wheels. The central guide rail may be the usual T-rail employed in the construc- 60 tion of ordinary railway tracks, and in the elevated railway this rail is arranged so that its upper surface is level with the top or broad surface of the girders or sleepers B. This elevated structure accommodates high 65 speed trains which consist of an electrically propelled car or locomotive E and one or more passenger coaches or "trailers" F which are

coupled to the car or locomotive E. This propelled car or locomotive E is provided with a long frame work e forming the rear truck 70 and a means for pivotally supporting the front truck e'; and these trucks e, e', are connected by a vertical king bolt e² to enable the front truck e' to turn horizontally and follow the line or curves in the track.

75 G is the rear axle which has suitable bearings in the rear part of the truck e, and on this axle are fixed the large central wheel H and the two carrying wheels I, I. Said central wheel H is provided with peripheral flanges that form a deep annular groove in the wheel H to enable said wheel to travel on the central rail C of the track, while the carrying wheels I are devoid of flanges and provided with broad bearing treads adapted to 80 ride or bear on the broad girders or sleepers B. To this axle G is geared an electric motor (not shown) which is carried by the car E for imparting motion to the axle to propel the car; and the body of the car is so hung or arranged that the weight thereof is thrown principally on the rear carrying wheels I to 85 secure the traction or friction between the broad wheels I and the girders or sleepers necessary for the propulsion of the car. The electric motor may be supplied with a current of electric energy from an overhead or a track conductor, but this is not an important factor 90 in my railway system forming the subject of the present application, as such conductor may be arranged, and supplied with energy, in any preferred manner and by any suitable means.

95 The front truck e' of the car E sustains an axle or shaft J which carries smaller broad bearing wheels j, j, at its ends to enable the latter to ride on the broad girders or sleepers; and this front truck also sustains the shafts k, k', of the flanged guide wheels K, K', which are arranged in line with each other and situated at the front and rear respectively of said front truck e', said aligned wheels K, K', being each provided with peripheral flanges which are spaced to form a deep annular groove in the periphery of the wheel to enable 105 said wheels to follow and keep to the central guide rail around the curves of the track. The broad flangeless wheels I, j, that run on the girders or sleepers are designed to sustain the weight of the car and its load, while the grooved aligned wheels H, K, K', serve to 110 guide the car along the line of the central guide rail so that in elevated structures it is not necessary to use a heavy rail for the central guide rail C as the latter is not designed to sustain a part of the weight of the car although it may be arranged to do so. The front part of the car E is sustained by hangers 115 pivotally connected to the forward truck e' while the rear part of the car is mounted on suitable springs; and these sustaining devices and the construction of the car body and tracks may be of any form or character having 120 the approval of persons skilled in this art.

The propelled car or locomotive E has the front sides made inclined or converging toward each other, and the roof is slanted or inclined upward and backward from the front 5 end of the car, and furnished with the usual windowed pilot compartment for the accommodation of the motorman.

The passenger coaches or trailers F are furnished with the front and rear trucks L, L', 10 each of which carries the axle l provided with the broad flangeless wheels l' adapted to travel on the girders or sleepers B; and each truck is further provided with the flanged wheels M, M', situated at the front and rear 15 of the truck and in line with each other to ride upon the central guide rail C.

In the surface railway, I use a single rail track on which slowly moving cars N are designed to run and which stop at frequent intervals for taking on and letting off passengers. This rail O of the surface line is laid or arranged so that it lies above the surface of the ground a short distance, and it is designed to bear its proportion of the weight of 25 said car body, which in this instance is arranged or hung so that a part of the weight thereof is thrown on the single rail O. The car N has the front and rear trucks, the former being furnished simply with the flanged 30 aligned guide wheels n, n, in the middle thereof to ride upon the rail O while the rear driving axle has a motor geared thereto and is provided with the large flanged driving wheel and with the large broad flangeless wheels. 35 These broad flangeless wheels of the rear truck in the surface car are designed to run on the surface of the ground, although planks or sleepers may be provided for said wheels when the rail O is laid on ground which does 40 not admit of the wheels bearing thereon, but this is optional.

The surface railways may be situated directly beneath the elevated track, or they may branch therefrom in any or every direction 45 to accommodate different sections of the surrounding country and transmit the residents thereof to a main station, from whence they can have quick passage to a central or any one of the main stations on the elevated rail- 50 way.

The operation and advantages of my invention will be readily understood and appreciated by those skilled in the art from the foregoing description taken in connection with 55 the drawings.

I am aware that changes in the form and proportion of parts and details of construction of the devices herein shown and described as an embodiment of my invention can be made 60 without departing from the spirit or sacrificing the advantages thereof, and I therefore reserve the right to make such changes and alterations as fairly fall within the scope of my invention.

Having thus fully described my invention, what I claim as new, and desire to secure by Letters Patent, is—

1. In a railway system, an elevated track having the broad girders and central guide rail which accommodate respectively the 70 flangeless traction wheels and flanged central wheels of a car, and a single surface rail adapted to receive the flanged wheels of a car provided with traction wheels, substantially as and for the purpose described. 75

2. In a railway system, the elevated track comprising the broad girders or sleepers and a central guide rail between the main stations, an elevated car having its trucks provided with the aligned flanged central wheels 80 that ride on the central rail and the axles provided with the flangeless traction wheels that bear on the sleepers or girders, a single surface rail leading to a main station of the elevated line and a surface car provided with 85 central aligned wheels that ride on said single rail and having the traction wheels designed to sustain the car-body in its upright position, substantially as described.

3. In a railway system, an elevated track 90 comprising a central guide rail and the broad smooth sleepers situated parallel to, and in substantially the same horizontal plane with, said central guide rail, an elevated car having at its rear end an axle which carries a 95 central flanged wheel adapted to the middle rail and provided at its ends with traction wheels which normally ride upon the broad sleepers of the track, said car having a pivotal front truck which sustains an axle carrying traction wheels adapted to the side sleepers and provided, in advance and rear of said axle, with independent flanged guide wheels which align with the rear guide wheel of the car and are so disposed as to normally 105 ride upon the central guide rail, for the purposes described, substantially as set forth. 105

4. In a railway system, the elevated track comprising a central guide rail and the side girders or sleepers, an elevated car having its 110 forward pivoted truck provided with the central flanged wheels that ride on said central rail and with the traction wheels to bear on the girders, and a rear power axle provided with the flanged wheel in line with the flanged 115 wheels of the forward truck and with the broad flangeless traction wheels that bear on the girders or sleepers of the track, substantially as described.

5. In a railway system, the combination 120 with a guide rail, of a car, the truck connected with said car and carrying a group of flanged guide wheels all disposed in the longitudinal center thereof, and the transverse axle journaled in the truck and provided at 125 the ends with broad flangeless traction wheels designed to normally bear on a smooth surface to sustain the greatest weight of the car body, as set forth.

6. An elevated railway comprising a track 130 embodying a central guide rail between two sleepers or girders which are built up of sections united laterally together to break joints and present a flat smooth upper surface, a

car, the trucks connected with said car and each carrying a group of flanged guide wheels disposed to ride on the central rail and the transverse axles journaled in said trucks and provided with broad traction wheels which ride on the smooth sleepers or girders, substantially as described.

In testimony whereof I affix my signature in presence of two witnesses.

CHARLES H. BARROWS.
